LENS GRINDING AND POLISHING MACHINE

Perry Okey, Columbus, Ohio, assignor to Perry-Lowell & Co., Columbus, Ohio, a partnership

Application June 27, 1945, Serial No. 601,749

9 Claims. (Cl. 51—134)

1

The present invention relates to a lens making machine and more particularly to a machine for abrading or grinding a plurality of lenses simultaneously, in which machine there is provided a plurality of work performing stations, each performing a slightly different function upon the glass, the machine being provided for progressively moving the lenses from station to station.

One of the objects of the present invention is to provide a machine which will simultaneously abrade the plurality of lenses at different work performing stations and which only a predetermined amount of material is removed at each station although the time for removing the desired amount may be greater at one station than the other. In carrying out this object, it is a further object of the present invention to provide for relative rotation by the abrading element and the lens element and to bias one toward the other but to limit the extent of the biasing movement so that after the necessary abrading operation is performed, the relative rotation may continue without further removal of material.

In carrying out the foregoing object, it is a further object of the present invention to provide a plurality of supports, one for the abrading element and one for the lens, which supports are moved toward one another during the abrading operation, and more particularly, one of the supports being in the form of a lever in which the pivot for the lever is disposed in a plane intersecting, substantially at right angles, the axis of the rotating element carried by the other support at the engaging surfaces of the two elements.

It is a further object of the present invention to provide a signal for the operator indicating when all of the abrading functions, being performed, are completed.

In carrying out the last mentioned object, it is a further object of the present invention to utilize the stops, which limit the extent of movement of the element being abraded and the lens element toward one another, as an electrical contact in a circuit, the circuit being so arranged as to give the signal after each of the separate abrading functions are completed.

It is still another object of the present invention to utilize a pressure responsive system, such as a hydraulic system, to effect certain relative movement between the abrading element and the lens element, and to effect the shifting of the lens from station to station by hydraulic mechanism, and in carrying out this object, it is a more specific object of the present invention

2

to provide a valve which is selectively operated either to effect relative movement between the abrading element and the lens element or to effect the station changing function, control mechanism being provided for preventing one of the hydraulic mechanisms operating prematurely so that the proper sequence of functions to be performed is assured.

In other words, it is another object of the present invention to interconnect hydraulic mechanism in such a manner that parts actuated by one of the pistons must be in a predetermined position before the other hydraulic mechanism can perform its function.

15 In carrying out certain of the foregoing objects, a table is provided having a plurality of work performing stations and this table is, from time to time, rotated a part of a turn. To accomplish this, there is provided a hydraulically operated piston and ram connected with the table by a clutch. When the piston moves in one direction, the table is advanced a part of a turn and is resiliently retained in the new position while the piston is retracted.

20 A still further object of the present invention is to impede the speed of the piston as it approaches the end of its stroke so as to prevent the momentum of the moving table from traveling beyond the station at which the succeeding work is to be performed.

25 A still further object of the present invention is to prevent the flow of actuating fluid to the cylinder provided for accomplishing the rotation of the table until the table has been moved, in an axial direction, to a predetermined distance, whereby the abrading and lens elements are completely separated from one another prior to the succeeding partial rotation of the table to the next station.

30 40 Further objects and advantages of the present invention will be apparent from the following description, reference being had to the accompanying drawings wherein a preferred form of embodiment of the invention is clearly shown.

45 In the drawings:

Fig. 1 is a top plan view showing a machine having five abrading stations and one load station;

50 Fig. 2 is a sectional view taken on line 2—2 of Fig. 1;

Fig. 3 is a fragmentary sectional view taken on line 3—3 of Fig. 1;

55 Fig. 4 is a fragmentary sectional view taken on line 4—4 of Fig. 2;

Fig. 5 is a fragmentary sectional view taken on line 5—5 of Fig. 1;

Fig. 6 is a view similar to Fig. 5 but showing certain elements in different positions;

Fig. 7 is a diagrammatic view of a hydraulic system showing the position of the valves after the completion of the partial rotation of the table, but before the piston is retracted;

Fig. 8 is another view of the hydraulic system showing the position of the valves just after the work table has been moved into abrading position;

Fig. 9 is a fragmentary sectional view taken on line 9—9 of Fig. 2;

Fig. 10 is a wiring diagram of the motor for driving the spindles which carry the lens;

Fig. 11 is a wiring diagram of the signal circuit;

Fig. 12 is a wiring diagram of the circuit for the electric motors which drive the abrading elements;

Fig. 13 is a fragmentary sectional view taken on line 13—13 of Fig. 1;

Fig. 14 is a fragmentary view looking in the direction of arrow 14 in Fig. 3;

Fig. 15 is a perspective view of a lens blank showing a near vision surface and distant vision surface; and

Fig. 16 shows the finished blank severed for the purpose of making two bifocal lens.

In the drawings, attention is specifically directed to Fig. 3. One of the abrading elements is shown at 20 driven by a motor 21. The abrading element is in the form of a wheel 20 and is shown in an abrading position with a lens blank 23 suitably secured to a lens carrier 24 which, in turn, is carried by a spindle 25. Spindle 25 is driven by a gear 26 which, in turn, is connected by other gearing 27 to a motor 29. During the abrading operation, both motors 21 and 29 are operated so that rotating movements are imparted to the abrading wheel 20 and the lens blank 23, simultaneously. The directions of rotations of a wheel 20 and lens blank 23 may be the same or counter to one another but in either case or under either condition, abrading wheel 20 rotates at a much higher speed than the lens blank.

Motor 21 is mounted on an arm 31 of a lever 32 pivoted on pin 33. The other arm 34 of lever 32 is arranged to engage a stop 35. Due to the weight of the motor 21, the lever 32 tends to move in a counter-clockwise direction, as viewed in Fig. 3, and the abrading operation will continue until the lever 32 is brought to rest upon engagement with the stop 35.

By reference to Fig. 1, it will be apparent that six separate stations are provided. These stations are the loading station A and work stations B, C, D, E and F. The machine herein shown is used in the manufacture of bifocal lens which are circular in plan and later severed in two pieces to provide two semi-circular bifocal lenses. The lens blank 23 is shown in Fig. 15, having a near vision field 37 and a distant field 38. The lens blank 23 and the lens blank holder 24 are placed on the spindle 25 at the load station A during the time that the abrading operations are taking place at stations B to F, inclusive. After the specific function is performed at each of the work stations, as indicated to the operator by a signal light, the lens blanks will be advanced, in a clockwise direction, one-sixth of a revolution where the next operation will be performed on the lens blank. Rough grindings are effected on the distant vision surface 38 at stations B and

C. At station D the last grinding or fine grinding is effected for surface 38. Rough grinding of near vision surface 37 is effected at station E. Fine grinding of surface 37 is effected at station F.

Referring now specifically to Fig. 2, there is shown a main base 40 including a bottom wall 41 and a cylindrical side wall 42. The bottom wall 41 is provided with reinforcing webs 43 and the top side of the bottom carries a cylindrical standard 45 having a flanged base 46 secured to the bottom 41 by bolts 47. A cylinder 48 surrounds but is spaced from the standard 45, thus forming a fluid chamber 49 therebetween. This cylinder 48 is secured to the base by bolts 50. The top of the cylinder is provided with a circular groove 52 which is filled with ball bearings 53. A hub 54 surrounds the standard 45, the standard 45 functioning as an axle for the hub.

The hub 54 is provided with an extension in a form of a table 56 and which is adapted, at times, to rest upon the ball bearings 53 for the ready rotation of the hub. The lower part 57 of the hub 54 telescopes into the chamber 49 between the cylinder 48 and the axle 45 and at the lower end thereof is provided with a fluid packing 58.

When liquid is admitted to the chamber 49 through the pipe 60, the piston formed by the part 57 and the integral hub 54 and table 56 will be raised. As will appear more in detail hereinafter, this raising of the hub is utilized to bring the lens blanks 23 into contact with the abrading wheels 20.

From Fig. 3, it will be seen that the motor 29 which drives the spindles 25 is carried by the table 56 and therefore is translated to six different positions. The gears for driving the spindles 25 are also translated with the hub 54 and table 56.

Referring again to Fig. 2, it will be seen that the upper part of the hub 54 carries an upper table 62 which is secured in position by bolts 63. Upper table 62 carries a plurality of bearings 64 for gears 65 which, through idler gears 66, drive the gears 26 on the spindles 25. The gears are driven by a pinion 66 from the motor 29. Two of the bearings 64 are shown in detail in Fig. 2.

In the present invention, the motor 29 is shown of the three-phase type which is connected by three spring fingers 69 to anyone of six sets of three contacts 70 in an electric circuit. These sets of contacts 70 are carried on the underside of an inwardly extending circular flange 71 of a circular trough 72. The sets of contacts 70 are spaced 60° from one another. When the three fingers 69 engage all three contacts of any set of contacts 70, the motor 29 will be started and the spindles 25 will be rotated. From this, it will be seen that starting and stopping of the rotation of spindles 25 is controlled by the raising and lowering of the hub 54, that is, when the hub 54 is raised to a predetermined level, the spindles will start to turn, and, when the hub is lowered, rotation of spindles stops.

The position of the hub 54 is also closely and accurately indexed by the raising of the hub. For this purpose, there are provided a plurality of upwardly extending tapered pins 73 on the top of table 62. Preferably six of these pins are provided, arranged in a circle and disposed 60° from one another; these pins are arranged to be received simultaneously by six sockets 74 which are also tapered and formed in the platform 75. Platform 75 is secured to the standard 45 by a series of bolts 76. The pins 73 and the sockets

74 are formed of hardened steel and are ground to fitting relation after assembly on the respective table 62 and platform 75. The tapered pins 73 and sockets 74 insure the proper location of table 62 when the table has been moved to its extreme upper position. The tops of these sockets 74 are closed by caps 71.

As will be seen from Fig. 12, motors 21 are connected in parallel through a three-pole switch 18 and this switch is opened and closed by a push rod 19 (see Fig. 8) which extends through and is guided by platform 75 and which is raised and lowered for performing the switch operation, by the table 62. From the foregoing, it will be seen that when the blanks 23 are brought into abrading relation with the abrading wheels 20, spindle driving motor 29 will be in operation and the abrading motors will be also in operation.

Each lens blank 23 is adjustably secured for rotation at a predetermined height. The vertical adjusting mechanism for the spindle height is shown in Fig. 3 and the spindle can be shifted axially, that is vertically, by a hand wheel 80. Six sleeves 81 are carried by the periphery of the table 62 and each of the lower parts of these sleeves is threaded at 82 to receive the threaded hand wheel 80. The hand wheel 80 is so connected to a sleeve 84, disposed in the hub 81, so as to raise and lower the sleeve 84. The spindle 25 is carried by the bearings 83, suitable shoulders 86 being provided on the spindle 25 which cooperate with the inner races and an interposed sleeve 88 to relatively fix the axial position of the spindle 25 with respect to the sleeve 84. Thus, by turning the wheel 80, the spindle 25 can be moved axially relative to the table 62. The gears 27 are made sufficiently wide to take care of all normal adjustments effectable by the wheels 80.

The height of the lens blank 23 may be determined by a gauge 90, see Fig. 5. This gauge is carried by a lever 91 pivoted at 92 to a standard 93 which, in turn, is carried by the platform 75. After the lens blank and holder assembly is placed in position at the loading station, the lever 91 is swung downwardly by the operator by handle 95 and if the lens blank is not at the proper height, the hand wheel 80 is turned in one direction or the other in order to bring the top surface of the lens blank at the proper height.

When the work at each specific station has been completed, the fluid is released from the chamber 49 and the hub 54 and tables 56 and 62 carried thereby are lowered until the entire hub section 54 rests upon the balls 53. Of course at this time, the circuit to the motor 29 is interrupted at 10 and the circuit to the motors 21 are interrupted at 18. Switch 18 is of the type which is normally biased to open circuit position by a spring and when the push rod 19, therefor, has released the switch, the switch automatically opens.

The next operation in the sequence is to rotate the table 62, 60°. This rotation is effected by a ram 98, clutch 99 and pins 100. Six of these pins depend from the table 56 and are arranged in a circle concentrically with the axle 45. Ram 98 is actuated by a piston 102 disposed in the cylinder 103. The clutch 99, in the form of a hook 104, is pivoted on the ram 98 at 105. This hook is normally urged inwardly by a spring 106. In Fig. 9, the ram 98 is shown in its retracted position.

When fluid is admitted to the cylinder 103, the ram 98 and hook 104 will be moved to the right. The hook 104 will engage one of the pins 100

and upon one stroke will cause tables 56 and 62 to be rotated 60°. The flow of fluid through the cylinder 103 is through a valve 107 and this valve is not opened until the hub 54 has reached substantially its lowermost position. The valve 107 is actuated by a lever 108 pivoted at 109. The end of the lever carries a roller 110 which is engaged by the bottom side of the table 56 when the table 56 reaches substantially its lowermost position.

The hub 54 is yieldingly retained in position into which it is moved by the hook 104. The mechanism for accomplishing this is shown in Fig. 9 and comprises a bell crank lever 112 which is pivoted at 113. Lever 112 includes an arm 114 for carrying two spaced rollers 115 which are arranged to substantially straddle one of the pins 100. These rollers are yieldingly urged against the pins 100 by a spring 116. When the piston 102 and the ram 98 are retracted, the bell crank lever 112 retains the hub 54 in its new position. The left end of the hook 104 is provided with a camming surface 117 which engages the pin 100 then lying in its path and therefore, by compressing spring 106 permits the hook to slide beyond said pin 100 and after the apex of cam 117 passes the pin 100, the spring expands, causing the hook 104 to come to rest in the position shown in Fig. 9.

30 The movement of the hub 54 is decelerated toward the end of its movement and this is accomplished by impeding the flow of fluid to the cylinder 103 as the piston 102 approaches the end of its stroke. Referring to Figs. 7 and 8, it will be seen that the piston carries a valve stem 119 which in turn carries a tapering valve 120 which controls the flow of fluid to the cylinder 103 through the valve seat 121. Valve seat 121 is interposed between a valve chamber 122 and cylinder 103. The tapering valve 120 decreases the flow of fluid to the cylinder 103 as the piston 102 approaches the end of the stroke. In this manner, the deceleration is such as to substantially eliminate momentum of the moving mass, which momentum would carry the table 56 beyond the stops predetermined by the rollers 115 and pins 100.

40 Pins 100 also open a valve 123 and retain the valve open as long as the hub 54 is in the position in which the grinding operation is to take place. A spring 124 normally urges valve 123 to the closed position. However, each of the pins 100 is arranged to open the valve through the linkage indicated at 125. Valve 123 is arranged to control the flow of fluid from the pump and to and from the cylinder 49.

50 Thus valve 123 prevents flow of liquid to the chamber 49 except when the table 56 is so located that the pins 100 open the valve 123 (i. e. so located that when raised the pins 73 will register with the holes 74 and the lens carriers 24 will be properly positioned relative to the abrading wheels 20).

60 Referring now to the diagrammatic view, Fig. 7, 65 of a hydraulic system, which shows the position of the valves and mechanism just after the clutch has 70 moved the hub 54 but before the clutch has been retracted, the pump is shown at 126 which is arranged to withdraw fluid, preferably liquid, from the reservoir 127 by pipe 128 and force the fluid into a pipe 129. Fluid is returned to the reservoir 127 through a drain 131. A high pressure relief valve 132 is interposed between pipes 129 and 131 to prevent the building of excessive pressure. A hand operated valve 134 determines

the course of flow of the high pressure fluid. As shown in Fig. 7, the valve 134 connects the cylinder 103 with the pump through pipe 129, valve passage 135, pipe 136, valve 107 and pipe 137. Fluid has been drained from the right of piston 102 by pipes 138, 139, valve passage 140 and drain 131. It will be observed that valves 107 and 123 are being held open due to the lowered position of the table 56 and by one of the pins 100. Now when it is desirable to raise the table 62 so as to bring the work into abrading relation with the wheels 20, the hand valve 134 is shifted to the position shown in Fig. 8 so that valve passage 140 connects the high pressure pipe 129 with the pipe 139 causing fluid under pressure to enter the main cylinder chamber 49 and raise the piston 57 carrying the hub 54 and tables 62 and 56. Liquid under high pressure will also flow from pipe 139 through pipe 138 into the cylinder 103 to the right of piston 102, thus causing the clutch to be retracted and moved to the position shown in Fig. 9 so that the clutch will be conditioned for turning the hub 54 on the next succeeding operation. It will be observed from Fig. 2 that the valve 107 is closed substantially immediately after the table 56 starts to rise.

A pipe 142 is connected with pipe 137. This pipe 142 carries a restrictor 143 which in turn is connected by a pipe 144 to the reservoir 127. The purpose of the pipes 137 and 144 is to drain the left side of the cylinder 103 after valve 107 is closed; the restricted passage 145 in restrictor 143 limits the flow therethrough so that the clutch returns in a smooth manner. However, the primary purpose of the restrictor is to prevent the short circuiting of the fluid from the pump to drain at the time it is desirable to move the piston 102 to the right. The resistance of the restrictor is such that it drains considerably less fluid than that pumped by the pump whereby, when the pump is operating and the valve 107 is open and the valve 134 is in the position shown in Fig. 7, the piston 102 will be moved with a determined force to the right.

After all of the grinding operations have been completed at the specific stations, it is necessary to shift the work to the next succeeding station. To accomplish this, it is necessary first to lower the blanks from the abrading wheels 20. To accomplish this, the hand operated valve 134 is shifted from the position shown in Fig. 8 to the position shown in Fig. 7. At this time the valve 107 is still closed. However, valve 123 is still open by reason of the position of the pin 100. Valve 123 remains open because the pin 100 merely moves vertically. Fluid drains from cylinder chamber 49 through pipe 60, valve 123, pipe 139, valve passage 140 and pipe 131. The weight of the tables, hub, etc. forces the liquid to drain. Just before the table and other lowered parts reach their lowermost position, roller 110 of valve 107 will be engaged by the underside of table 56 to open valve 107 and, since the high pressure side of the pump is connected, through the passage 135 and valve 107, to the left side of the piston 102, the piston and the ram 98 will be moved to the right causing hook 104 to rotate the tables and the parts carried thereby a one-sixth turn. It is to be observed that immediately after the tables start to lower, as previously described, the circuit to the motor 29 will be interrupted at switch 69 and the circuits to the motors 21 will be interrupted by the switch 78. After the ram moves the

rest because valve 120 is closed upon valve seat 121 and one of the pins 100 is detained by the rollers 115. Then the operator shifts the hand operated valve to the position shown in Fig. 8 to cause the elevating of the tables, as previously described, with the accompanying closing of switches 69, and 78 to start all of the motors.

As will later be explained more fully, cooling liquid is supplied to the lens blanks being ground and to the abrading wheel grinding the lens during the abrading operation. This liquid is thrown centrifugally from the blanks and the abrading wheels. Means are provided to prevent this cooling fluid from being scattered or thrown from the machine and to prevent it from escaping through the bearings for the spindles. A casting 146 partially surrounds each of the spindles and lens carriers. Each casting 146 has a circular bottom section 147 which entirely surrounds the associated spindle 25. Each casting 146 is also provided on the inward side of the spindle with a semi-circular upwardly extending section 147a. The circular bottom section 147 is secured to the table 62 by means of screws. A removable semi-circular section 150 complements the section 147a so that the sections 147, 147a and 150 form a casing for substantially enclosing the lens blank carrier 24. The removable section 150 is provided with a handle 151, for removing that portion of the casing when removing ground lens and inserting lens blanks to be ground. It will be noted from the left hand side of Figure 15 that the removable section 150 at its bottom edge rests upon the top of the table 62 inside of the circular lower portion 147 of the casting 146. The casing 146 formed by the portions 147, 147a and 150 is open at the top as shown at 149 so that the lower part of the motor shaft and the abrading wheel 20 may during the abrading operation extend down through the opening 149 and contact with the lens blank. Thus the casing 146 formed by the portion 147, the portion 147a and the portion 150 confines the flow of the liquid. The liquid after striking the inside walls of the casing 146 drops down into a basin which is formed by the circular wall 147. This basin is designated in Figure 3 as 148a.

During the abrading operation, the operator places a lens carrier 24 carrying an unground blank on the spindle 25 at station A, sets the height of the top of the blank by manipulating the wheel 80, checks the same by the gauge 90. After completing this operation, casing section 150 is placed about the lens blank. The gauge 90 is then swung manually out of contacting position with the lens blank 23 by the handle 95 and the lever 97 then rests upon a spring pressed plunger 152, the spring, not shown, being carried within the casing 153, the purpose of the spring being merely to absorb the shock of the backward movement of the lever 97.

In the event that the operator fails to move the gauge from the position shown in Fig. 5 to the position shown in Fig. 6, means is operated automatically to effect this movement upon the upward movement of the table 62. When the lever 97 is in the position shown in Fig. 5, the center of gravity thereof is to the left of the pivot pin 92. One end of a spring 156 is fastened to the platform 75 and the other end is fastened to a link 157. Link 157 has a reduced portion 158 which fits loosely within a hole 160 in the platform 75 and extends below the platform 75 and is arranged to be actuated by the table 62. This link

157 has a longitudinal slot 161 therein which receives a pin 162 secured to the lever 97. Pin 162 is free to move in the slot 161 when the link 157 is in the position shown in Fig. 5. However, as soon as the table 62 is lowered, the spring 156 and gravity will force the link 157 downwardly pulling the pin 162 downwardly so as to tilt lever 97 to the position shown in Fig. 6 whereby, the casing sections will not strike the gauge when they are moved by the next turning of the table.

By the arrangement herein shown, any desired contact pressure can be maintained by the abrading wheels 20 and the lens blank and when desirable, this pressure can be reduced to substantially zero. As previously stated, the motors 21 are pivotally mounted and the weight is distributed so that the lever 32 tends to move in a counter-clockwise direction as viewed in Fig. 3. The degree of pressure can be adjusted by varying the tension of supporting springs 165. These springs are arranged in pairs, one end of each being connected to the arm 31 and the other end being connected to a turn buckle 166 which in turn is connected by a rod 167 to a bracket 168. This bracket 168 is carried by a post 169 which is threaded into the top of platform 75 at 170. Thus, it will be seen that by turning the turn buckles 166 on the threaded rod 167, any desired pressure can be maintained between the abrading wheel 20 and the surface of the lens blank.

The angular relationship of the axes of each of the abrading elements 20 and each of the spindles 25 can be varied and held in adjusted position. This is accomplished by shifting each of the axes of the motors 21. The motor shaft 172 of each of the motors 21 is carried in a sleeve type bearing 173 which, in turn, is secured in a sleeve 174. A circular flange 175 is formed integrally with and projects from the side of the sleeve 174. A narrow hub 176 extends from the side of the flange 175 and the hub and the flange are concentrically drilled and threaded to receive a bolt 178. The forward end of the arm 31 is provided with a recess 179 which receives the hub 176, and, a hole 180 is drilled concentrically with the recess for receiving the bolt 178. When the bolt is drawn tightly, the sleeve 174 is clamped in position on the arm 31. A washer 181 is interposed between the bolt head and the arm. The top side of the end of arm 31 is bifurcated, the furcations being shown at 183 and a finger 184, formed integrally with the sleeve 174, extends between the furcations 183. Each of the furcations is threaded to receive screws 185. Each of these screws extend through one of the furcations and the ends of the screws are arranged to engage the finger 184, one on one side of the finger and one on the other. To adjust the axis of the motor 21, the bolt 178 is loosened and the screws 185 are manipulated to move the finger to cause the rotation of the sleeve 174 and likewise the motor about the bolt 178. The bolt 178 is then tightened to clamp the sleeve in adjusted position.

An index line 186 is formed on the extreme forward end of the flange 175 and index lines 187 are formed on the extreme forward end of the arm 31. After the axis of the shaft 172 is shifted to the desired position so as to provide the proper curvature of the surface of the lens being ground, the relative position of the line 186 with respect to the lines 187 is recorded for the purpose of reshifting to this exact position in the event that it is desirable to return to the same curvature after the axis of the shaft 172 has

been shifted for abrading another lens of a different curvature.

The height of the abrading wheel 20 is adjusted by shifting the motor vertically in the sleeve 174. For this purpose, there is provided an ear 188 on the lower part of the motor housing and an ear 189 on the sleeve 174. A bolt 190 is threaded into the ear 188 and freely passes through the ear 189 on the sleeve 174. Adjusting nuts 191 are disposed on the opposite sides of the ear 189 and, when clamped against the ear, hold the ear 189 in an adjusted position. To adjust the height of the abrading wheel 20, the positions of the nuts are shifted. For example, to raise the wheel 20, the top nut is loosened and the bottom nut is turned so as to slide the sleeve 174 upwardly. When the desired height is reached, the top nut is drawn tightly onto the ear 189.

It is also necessary to shift the axis of the abrading wheel 20 horizontally in order to define the relative widths of the vision field 37 and the distant field 38. Although the positions of the arms 31 are shown in which the abrading of the lens blanks take place inwardly of the axes of the lens blanks, it is desirable, at times, to cause the abrading by the wheels 20 to take place outwardly of the axes of the lens blank. This shifting is accomplished by shifting the pivot pin 33 for the lever 32. The pivot pin 33 is carried by a bracket 192 including base 194 having a slot 195 which extends longitudinally of the lever 32. The bracket is slid upwardly from the hole that receives the pin 33 and a draw bolt 196 is provided for drawing the top parts of the bracket together to tightly clamp the pin in position. The bracket 192 is clamped to the platform 75 by a bolt 197. This bolt extends through the slot 195 and when loosened, permits horizontal or radial shifting of the bracket 192 for moving the axis of the shaft 172 either toward or away from the axis of spindle 25.

In order to insure accurate radial movement of the bracket 192, when it is being shifted horizontally, there is provided a tongue 199 on the bottom of the base 194 of the bracket which slides in a radially extending groove 200 in the platform 75. The shifting of the bracket 192 is accomplished by turning either of two bolts 202 or 203. For this purpose, there is provided a block 204 secured to the platform 75 by a bolt 205. The block 204 is threaded to receive the screw 202. Head 207 of bolt 202 engages the outer edge of base 194. The end of bolt 203 abuts block 204 and is threaded in the base 194. When the bolt 197 is loosened, the bracket 192 can be shifted to the right or left as viewed in Fig. 4. If it is desirable to move the bracket to the right or radially inwardly, the bolt 203 is turned so that it moves to the left i. e. away from the block 204. Then bolt 202 is turned so that the head 207 draws the base 194 of the bracket 192 to the right. When the desired position is attained, bolt 197 is tightened to clamp the bracket 192 in position. If it is desirable to move the bracket 192 to the left or radially outwardly, bolt 197 is first loosened and then bolt 202 is moved to the right so that there is a clearance between the head and the edge of the base 194. Then bolt 203 is turned so that the threads thereof, after the right hand end engages the block 204, forces the base 194 to the left. Again the bolt 197 is tightened to clamp the bracket 192 in position.

Micrometer calibration is provided for determining the exact position of the bracket 192 for the purpose of resetting the axis of a spindle 172

11

to an exact position previously desired for certain size vision and distant fields. For this purpose, the stationary part 209 of a micrometer 210 is secured to the inner edge of the bracket 192 by a set screw 211. The movable part 212 of the micrometer 210 is threaded on to the stationary part 209 in the usual manner. The right hand end of the movable part 212 is arranged to engage an abutment 214 on a block 215 secured to the platform 75. When the desired setting is effected, the movable part is moved to the right until the end thereof engages the abutment 214 and a reading taken on the calibration of the micrometer. In the event that the machine is used alternately for different area vision fields in which the bracket 192 is shifted, it can be readily reset to the exact position by reference to the previous recordings taken for the desired settings of the particular area of the field.

From the foregoing, it will be seen that the abrading wheels 20 can be individually shifted in all the directions necessary, namely, in three directions, for the purpose of varying the areas of the respective near vision and distant fields and for the purpose of individually varying the curvatures of the respective fields. If it is desirable to change the width of the near vision field, the bracket 192 carrying the pivot 33 for arm 31 is shifted horizontally. To change the curvature, the axis of rotation of wheel 20 is shifted by rotating sleeve 174 on arm 31. Whenever either of these corrections or changes is made, it is usually necessary to again reset the height of the wheel 20 and this is accomplished by manipulating the nuts 191. For most accurate results, it is desirable that the abrading surface of the wheel be in plane intersecting the pivotal center of the pin 33 and the bottom of stop 35.

The usual working or cooling liquid is delivered to the abrading and abraded surfaces during the abrading operation and this liquid is delivered to these surfaces at each of the stations by a tube 218. The nozzle end 219 of this tube is directed inwardly so as to flush the turning surfaces. A tube extends through a bracket 221 carried by the sleeve 174 and the upper end thereof is provided with a shut-off valve 222. Fluid is delivered to the shut-off valve 222 by a flexible hose 223 which is connected by a check valve 224 with a manifold 225 through a pipe 226. The check valve is provided with disc type valve 227 yieldingly held in position by a spring 228. The top wall 229 of the valve is removably held in position by a removable stirrup 230 which latter is held in place by a screw 231. A valve 234 (Fig. 1) controls the flow of fluid to the manifold 225. A hose 235 conducts the fluid to the valve 234. Cooling liquid is delivered to the abrading surfaces only during the abrading time and the flow thereof is stopped automatically at the valve 234 as soon as the table 62 is lowered, and, the valve 234 is not opened until just prior to the start to the next abrading operation. For this purpose, there is provided a push rod 236 (Figs. 7 and 8) which opens the valve 234 when the table 62 forces the push rod 236 to valve opening position. Valve 234 is of the type which automatically closes when the pressure, by the push rod 236 thereon, is released. The valves 224 are forced open by hydraulic pressure on the cooling liquid and as soon as this pressure is released, due to the closing of the valve 234, the spring 228 closes the valve 227 on its seat. The purpose of the check valves 224 is to prevent any of the

12

tubes 223 from siphoning liquid from the manifold during the period when valve 234 is closed.

There will be some drip from the tubes 218 after the valve 234 is closed and for this purpose there is provided a plurality of drip pans 238 which are secured to and span the upper part of casing sections 147. Each of the drip pans is provided with an outlet 239 which is connected by downwardly extending pipes 240 which lead to the basin 148a therebelow. These basins are connected by drip pipes 242 with the drain chamber or trough 72, whence the cooling liquid is returned to a settling chamber, not shown. Liquid is pumped from the settling chamber to the pipe 235 by a pump, not shown. The usual type of cooling liquid is employed and comprises a mixture of soluble oil and water.

Referring specifically to Fig. 1 and somewhat to Fig. 2, it will be seen that the three wires for conducting electric current to the motors 21 are indicated at 244. These wires lead to a switch box 245 whence they extend to and from the switch 18 through a conduit 246 to the switch box 245. In the switch box 245, they are connected to sockets 248 and then connected by plugs 249 and conduits 250 to the motors 21. This switch box is carried by the post 169 and rests upon the manifold 225, and is locked in position by set screws 251. The manifold 225 rests upon the bracket 168 and this bracket is held in position on the rod 169 by a set screw 253.

Again referring to Fig. 1, the pump 126 is driven by an electric motor 255 through pulleys 256 and 257 and belt 258.

The electrical circuit for the signal light 260 which is mounted on the stationary table 75 adjacent to the reloading station A in a position in which it is convenient for observation by the operator is shown in Fig. 11. The stops 35, which limit the swinging movement of the lever 32 and thereby the extent of downward movement of arm 31, carry stationary electrical contacts 261a and the ends of arm 34 carry contacts 261. All of the contacts 261 and 261a and the light 260 are connected in series circuit relation with a source of electrical energy herein shown as a battery 262. The circuit includes battery 262, wiring 263, light 260, wire 264, stationary contact 261a, contact 261, bolt 266, connector 267, wire 268 which connects with the next stationary contact 261a thus through all of the contacts 261 and 261a and all of the interconnecting wiring to wire 270 which lead to the opposite side of the battery 262. After all of the abrading operations are completed, all contacts 261 will be in contact with their respective contact stops 35 to thus complete the circuit to the signal light 260. The operator then shifts the lever 272 for actuating the valve 134 in the manner previously described.

Preferably, more than two sets of locating pins 73 and sockets 74 are employed for accurately locating the table 62 in position in which abrading takes place. By employing six sets, the resulting pressure between the table 62 and platform 75, when the table is forced into abrading position, is distributed equally circumferentially between the platform and table. This equal, circumferential distribution of pressure prevents distortion of the table and platform. Distortion of either table or platform would cause misalignment of the lens blank and abrading wheel.

Operation

While the operation has been described in connection with the preceding detailed description

of the device illustrating my invention, a general description of the more important features of the operation will be also given here. Referring to Fig. 1, it may be seen that there are six stations designated as A, B, C, D, E, and F at four of which there are motors 21, and at the other there is the gauge 90. During abrading operation there is a lens carrier 24 adapted to support a lens 23 also associated with each station. Each such lens carrier 24 is (as is shown more clearly in Fig. 3) mounted upon a rotatable spindle 25, such spindles being mounted on a movable table 62 and being adapted at times to be driven by gear trains from a motor 29. During abrading operation the electric motors 21 are mounted above the lens carriers 24 and at such times drive abrading wheels 20. The motors 21 are mounted upon pivoted arms 31 on a stationary table 75. The table 62 is rotatably mounted for rotation about the central axis of the machine as is shown more clearly in Fig. 2 and also is arranged for vertical movement from the position shown in Fig. 2 (in which the table 62 is lowered) to the position shown in Fig. 3 (in which the table 62 substantially contacts with the table 75). The rotation and the raising and lowering of the table 62 are each accomplished hydraulically.

The hydraulic means for raising and lowering the table 62 is shown diagrammatically in Figs. 7 and 8 and comprises the pump 126; connecting hydraulic lines 60, 129, 131 and 139 and the fluid chamber 49. The fluid chamber 49 is in effect a hydraulic cylinder having a piston 57 slidably mounted therein. As is shown in Fig. 2, the piston 57 is in reality a sleeve. This piston sleeve 57 carries movable table 62 on which the lens carriers 24 are mounted. It also carries a movable table 56 on which is mounted a motor 29.

The hydraulic means for rotating the table 62 is shown in Figs. 7, 8 and 9 and comprises the cylinder 103, the piston 102 therein, the extension 98 of the piston and the pivoted clutch lever 99 with its hook 104. The hook 104 is adapted at each reciprocation to engage one of the pins 100 and through the pins move the tables 56 and 62 through 60° of rotation.

It must be noted that when the tables 56 and 62 reach their uppermost positions the table 62 contacts and moves upward the two rods 79 and 236 (see Figs. 7 and 8). The push rod 79 operates the switch 78 (Figs. 1 and 12) to energize the motors 21 and thus the motors 21 are continuously rotating and revolving their abrading wheel whenever the tables are in the upper position. However, due to the stop provided by the contact 261 on the outer ends of the arms 34 of the levers 31 (see Fig. 3) the abrading wheels 20 do not grind the lens beyond the limit for which the operation is set. The valve rod 236 operates a valve 234 (see Fig. 1) which controls the flow of cooling fluid so that whenever the table 62 is in its uppermost position, cooling fluid under pressure is supplied to each of the abrading stations to keep the lens being ground and abrading wheel acting thereon cool during the abrading operation. The motor 29 is also energized and driven whenever and only when the table reaches its uppermost position. The contact 69 (see Fig. 2) is raised with the table 56 and contacts with one of the contacts 70 and through the circuit thus formed, electricity is thus supplied to the motor 29 to cause its operation when the tables are raised to their uppermost positions.

Assume that the table 62 is in the lowered position shown in Fig. 2. The operator places a

lens on the particular lens carrier 24 which is then at station A, removing the movable section 150 of the oil protecting cover 146 (see Fig. 3) in order to do so. He then operates valve 134 manually by means of the handle 272 (see Fig. 1) to move the valve from the position shown in Fig. 7 to that of the position shown in Fig. 8. Liquid driven by the pump 126 flows through the conduit 129, the valve 140, the conduit 139, the valve 123, and the conduit 60 to the fluid chamber 49. Fluid also flows through the conduit 138 to the cylinder 103 moving the piston 102 to the position shown in Fig. 8 but this has no effect on the table inasmuch as the cam surface 117 of the clutch lever 99 (see Fig. 9) causes that clutch lever to pivot against the action of the spring 106 and slide over the next pin 100 (preparatory to the next action of rotating the table 62). This does not disturb the position of the table 62 which is held releasably in position by the rollers 115 of the lever 114. Inasmuch as the lens 23 is not in a position to have any operation performed upon it, the operator immediately again operates the valve 140 moving it from the position shown in Fig. 8 to that of the position shown in Fig. 7. As may be seen, this connects the chamber 49 through conduits 60, 139 and 131 with the reservoir 127 and the weight of the tables 56 and 62 causes the tables together with the piston 57 to be lowered to the position shown in Fig. 7. When the tables reach the position shown in Fig. 7, the table 56 contacts with the rod of the valve 107, opening that valve and inasmuch as the pump 126 is supplying fluid under pressure through the conduit 129, the valve 134, the conduit 136 to the valve 107, the fluid under pressure may now pass through the conduit 137 to the cylinder 103 and force the piston 102 to the right (as shown in Fig. 7 and in Fig. 9). The piston 102 through the extension 98, the clutch lever 99 and the hook 104 rotate the tables 56 and 62, 60° in a clockwise direction as shown in Fig. 9. The valve is again moved to raise the tables as before. Another lens carrier will now be in the position of station A and another lens blank may be placed upon such lens carrier. The operation may be repeated but at this time the motor 21 at station B will operate the abrading wheel there to perform a grinding operation on the first lens. This grinding operation being completed, the arm 34 of the levers 31 will cause an electric circuit to be completed through all the contacts 261 (see Fig. 3) to operate the signal 260 and will give a signal to the operator that the operation is completed. The operator again operates the valve 134 manually to lower the tables and to rotate it. Then he operates the valve 134 again to raise the tables and places a new lens on the next lens carrier 24 at station A. This operation is continued until the original lens arrives back at station A. Thereupon the operator removes the lens which is now finished from the lens carrier at station A and inserts a new one in its place and so continues.

While the form of embodiment of the present invention as herein disclosed constitutes a preferred form, it is to be understood that other forms might be adopted, all coming within the scope of the claims which follow:

I claim:

1. In a lens grinding machine in combination, mechanism forming a plurality of work supports for lens blanks; mechanism forming a plurality of grinding tools adapted to be associated with lens blanks carried by the lens blanks sup-

ports; a fluid pressure circuit including a source of fluid pressure, pressure responsive means for successively moving one of said mechanisms to change the relative position of the work supports and tools, pressure responsive means for moving one of said mechanisms toward the other, a valve selectively movable for connecting the source of pressure either with the first or second mentioned means, a valve for controlling the flow of fluid to one of said pressure responsive means; and means responsive to operation of the other pressure responsive means for preventing opening of the second valve until the said mechanism actuated thereby has moved to a predetermined position.

2. In a lens grinding machine in combination, mechanism comprising a table rotatable about a vertical axis and having a plurality of rotatable lens blank supports; a plurality of rotatable grinding tools adapted to be associated with lens blanks carried by the lens blank supports; a fluid pressure circuit including a source of fluid pressure, pressure responsive means for successively rotating said table mechanisms to change the relative position of the lens blank supports and tools, pressure responsive means for moving said table mechanism toward the rotatable grinding wheels, a valve selectively movable for connecting the source of pressure either with the first or second mentioned means, a valve for controlling the flow of fluid to the second mentioned pressure responsive means and means responsive to the vertical movement of the table for preventing opening of the second valve until the table has been moved to a predetermined position by the first mentioned pressure responsive means.

3. In a lens grinding machine in combination, mechanism comprising a table having a plurality of rotatable lens blank supports; grinding mechanism comprising a plurality of abrading wheels adapted to be associated with lens blanks carried by the lens blank supports; a fluid pressure circuit including a source of fluid pressure, pressure responsive means for successively rotating said table to change the relative position of the lens blank supports and abrading wheels, pressure responsive means for moving said table vertically toward the abrading wheels; means responsive to vertical movement of the table for rotating the abrading wheels; means responsive to vertical movement of the table for rotating the lens blank supports; a valve selectively movable for connecting the source of pressure either with the first or second mentioned means, a valve for controlling the flow of fluid to the first mentioned pressure responsive means; and means responsive to the vertical movement of the table for preventing opening of the second valve until the second mentioned mechanism has been moved to a predetermined position by the second mentioned pressure responsive means.

4. In a lens grinding machine in combination, mechanism comprising a table having a plurality of rotatable lens blank supports; abrading mechanism comprising a plurality of abrading wheels adapted to be associated with lens blanks carried by the lens blank supports; a fluid pressure circuit including a source of fluid pressure, pressure responsive means for successively moving said table rotatably to change the relative position of the lens blank supports and abrading wheels, pressure responsive means for moving said rotatable table toward the abrading wheels, a valve selectively movable for connecting the

source of pressure either with the first or second mentioned means, a valve for controlling the flow of fluid to the second mentioned pressure responsive means, a valve for controlling the flow of fluid to the first mentioned pressure responsive means; means responsive to the vertical movement of the table for preventing opening of the second valve until the first mentioned mechanism has been moved to a predetermined position by the second mentioned pressure responsive means.

5. In a lens grinding machine in combination, a rotatable and vertically reciprocable table; a plurality of work performing stations associated with said table; a lens grinding mechanism associated with each of a plurality of said work performing stations; a fluid pressure circuit including a source of fluid pressure, pressure responsive means for rotatably moving the table from station to station, pressure responsive means for moving the table vertically to positions adjacent to said lens grinding mechanism, a valve selectively movable for connecting the source of pressure either with the first or second mentioned means, a valve for controlling the flow of fluid to the second mentioned means; and means responsive to the rotation of the table for preventing opening of the second mentioned valve until the first mentioned means has rotated the table to a work performing station.

6. In a lens grinding machine in combination, a rotatable and vertically reciprocable table equipped with a plurality of lens holding devices; a plurality of work performing stations associated with said table and each equipped with a rotatable lens grinding abrading wheel; a fluid pressure circuit including a source of fluid pressure, pressure responsive means for rotating the table from a position in which one of said lens holding devices is positioned adjacent to one of said work performing stations to a position in which said lens holding device is positioned adjacent to another of said work performing stations, pressure responsive means for reciprocating the table toward said abrading devices, a valve selectively movable for connecting the source of pressure either with the first or second mentioned means, a valve for controlling the flow of fluid to the first mentioned means; and means responsive to the operation of the second mentioned means for preventing opening of the second mentioned valve until the second mentioned means has reciprocated the table to a predetermined position.

7. In a lens grinding machine in combination, a table having a plurality of lens supporting devices; a plurality of work performing stations associated with said table and each having a lens grinding mechanism; a fluid pressure circuit including a source of fluid pressure; pressure responsive means for rotating the table from a position in which one of said lens supporting devices is associated with one of said work performing stations to a position in which said lens supporting device is associated with another of said work performing stations; pressure responsive means for reciprocating the table toward said work performing stations; a valve selectively movable for connecting the source of pressure either with the first or second mentioned means; a second valve for controlling the flow of fluid to the sec-

ond mentioned means; a third valve for controlling the flow of fluid to the first mentioned means; means responsive to the operation of the first mentioned means for preventing opening of the second valve until the first mentioned means has rotated the table to a position in which a lens supporting device is at a work performing station; and means responsive to the operation of the second mentioned means for preventing opening of the third valve until the second mentioned means has reciprocated the table to a predetermined position.

8. In a lens grinding machine in combination, a table having a plurality of work supporting devices; a plurality of work performing stations associated with said table and each having a lens grinding mechanism; a fluid pressure circuit including a source of fluid pressure, pressure responsive means for moving the table from station to station, pressure responsive means for moving the table laterally of the first mentioned movement, a valve selectively movable for connecting the source of pressure either with the first or second mentioned means, a valve for controlling the flow of fluid to one of said pressure responsive means; and means responsive to the operation of the other of said pressure responsive means for preventing opening of the second valve until the table has been moved to a predetermined position by said other pressure responsive means.

9. In combination, a stationary table; a rotatable table, one of said tables being movable toward and away from the other table; a plurality of working tools carried by one of said tables; a plurality of lens holding devices carried by the other said table; one of said tables having at least three sets of locating pins carried thereby and spaced thereabout and said other table having sockets for receiving all of said locating

18
means when the tables are moved toward one another; and means for moving said elements relative to one another.
